UNITED STATES PATENT OFFICE.

JOHN F. O'CONNOR, OF CHICAGO, ILLINOIS, ASSIGNOR TO WILLIAM H. MINER, OF CHAZY, NEW YORK.

COUNTERBALANCED ROLLER-BEARING.

1,360,781.

Specification of Letters Patent. Patented Nov. 30, 1920.

Application filed April 3, 1919. Serial No. 287,170.

To all whom it may concern:

Be it known that I, JOHN F. O'CONNOR, a citizen of the United States, residing at Chicago, in the county of Cook and State of Illinois, have invented a certain new and useful Improvement in Counterbalanced Roller-Bearings, of which the following is a full, clear, concise, and exact description, reference being had to the accompanying drawings, forming a part of this specification.

This invention relates to improvements in counterbalanced roller bearings.

One of the objects of this invention is to provide an anti-friction bearing of the true roller type and especially adapted for rail-way car side bearings, and wherein is employed a minimum number of parts so constructed that the anti-friction element will be returned to central normal position solely under the influence of gravity.

Another object of this invention is to provide an anti-friction bearing of the type above indicated and wherein are provided means for positively maintaining a predetermined relation between the anti-friction element and its retaining member in all positions of the anti-friction element.

Other objects of the invention are to provide an anti-friction bearing of the type above indicated so designed that the means for maintaining the relation between the anti-friction element and its retaining member also act as the means for returning the anti-friction element to its central normal position; to so design the parts that the anti-friction element has a full length bearing to thereby eliminate bending moments; and to render extremely sensitive the return of the anti-friction element to its central normal position under the influence of gravity after removal of the actuating pressure.

In the drawing forming a part of this specification, Figure 1 is a vertical sectional view taken through the ends of a car body bolster and a truck bolster showing my improvements in connection therewith in the form of an anti-friction side bearing. Fig. 2 is a top plan view of the anti-friction bearing proper shown in Fig. 1, parts being broken away to better accommodate the view on the drawing. And Fig. 3 is a vertical sectional view taken substantially on the line 3-3 of Fig. 2.

In said drawing, 10 denotes the underside

of a car body bolster and 11 the upper side of an opposed truck bolster. I have shown my improved bearing as secured to the truck bolster, and, as shown, the bearing comprises, broadly, two elements, to-wit: a retaining member or base casting designated A and an anti-friction element designated B.

The retaining casing or base casting A is of substantially hollow rectangular formation and has parallel spaced side walls 12-12, end walls 13-13 and lower corner lugs 14-14, perforated to accommodate rivets or other suitable securing means for attaching the member A to the bolster. On its interior, the member A is provided with a transversely extending shelf, indicated at 15, suitably supported by transversely extending ribs 16-16. To promote the life of the bearing, I preferably provide an insertible steel plate 17 mounted on top of the shelf or ledge 15. The plate 17 is inserted through suitable openings 18 and the side walls of the member A, and to retain the plate 17 in position, one end thereof may be bent down, as indicated at 19, to form a shoulder and a cotter pin 20 inserted through a suitable opening in the plate at the opposite end thereof on the outside of the adjacent side wall 12 of the member A. As clearly indicated in Fig. 1, the shelf 15 and plate 17 are disposed centrally lengthwise of the member A with a considerable clearance between each edge of the plate 17 and the inner face of the adjacent end wall 13. Furthermore, the combined shelf and plate 17 is so formed as to present the upper face or wear-bearing surface of the plate 17 at a considerable elevation above the bottom proper of the member A—the purpose of which will appear hereinafter. To facilitate the washing out of dirt or other foreign matter which may accumulate within the member A, the end walls thereof may be cut away, as indicated at 21-21.

The anti-friction element B, as shown consists of a main cylindrical section, indicated at 22, and a pair of substantially diametrically disposed, longitudinally extending, preferably integral depending weighted wings 23-23. As will be evident, the element B has an upper bearing surface 24 and a lower concentric bearing surface 25, both of equal radius, said surfaces 24 and 25 extending the full length of the anti-

100

105

110

friction element B and arranged to have contact for the entire length of the element B from one end to the other end thereof with both the bearing surfaces of the plate 17 and the underface of the body bolster 10, so that the element B is relieved of any bending moment and is subject only to compression strains.

The wings 23 are of similar formation and a description of one will suffice. Each wing 23 is of special formation and has an upper outer curved surface 26 and inner curved surface 27, a narrow lower inner flat face 28 and a relatively wide lower outer flat face 29. As will be evident from an inspection of Fig. 1, the wings 23 are so disposed with respect to the axis of the element B as to lower the center of weight of the combined roller section proper and the wings and locate said center of weight in a vertical line passing through the center of the roller section 22 and below the axis of the latter when the element B is in its central normal position. Furthermore, the wings 23 are extended downwardly so as to overlie the transversely extending edges of the plate 17. In addition, the maximum distance transversely of the anti-friction element B from one outer curved surface 26 to the other is made slightly less than the distance between the end walls 13-13 of the base casting A, thus leaving a slight clearance, as indicated at $c-c$, on each side of the element B. These clearances $c-c$ may be made as small as desired but preferably will be approximately one-eighth of an inch in a side bearing having a permissible rolling movement of two and one-quarter or two and one-half inches to either side of normal position. With this construction, it is evident that the possible off-setting bodily of the element B from vibration or jarring is positively limited to the amount of the clearance c , and, consequently, the anti-friction element B can never assume an accidental position which will not permit it to thereafter give a substantially complete full movement when brought into play. This is of extreme importance in anti-friction side bearings and overcomes one of the defects of substantially all rocker bearings heretofore employed where it has been possible for the rocker to be offset by vibration to such an extent that when the rocker is brought into operation the permissible rocking movement thereafter is much less than that actually required to effect the function of the bearing.

The curvatures of the surfaces 26 and 27 of the wings 23 are made so that the outer surfaces 26 will just clear the inner faces of the end walls 13 when either wing 23 is depressed, and the surfaces 27 will at all times clear the transverse edges of the plate 17 during a similar movement. The dotted

lines in Fig. 1 indicate one extreme position of the anti-friction element and it will be noted that the inner surface 27 of the lefthand wing clears at all times the lefthand edge of the plate 17, even though it moves thereunder during the rolling action. The outer surface 26 of the lefthand wing 23 clears the inner face of the lefthand wall 13 of the casting A until the extreme position is reached, when it may come in contact therewith and assist in preventing further rolling movement of the element B, the cylindrical section proper 22 thereof preferably coming into contact with the end wall 13 simultaneously with the contacting of the wing 23 with said end wall 13.

As indicated by the dotted line position of the anti-friction element B in Fig. 1, the narrow flat faces 28 of the wings are adapted to contact with the vertical faces 30-30 of the transversely extending shelf 15, and the flat faces 29 are adapted to simultaneously contact with the upper face of the truck bolster 11, both assisting in limiting the movement of the element B.

From the preceding description considered in connection with Fig. 1, it will be noted that the two sets of curved surfaces 26 and 27 of the wings will always coöperate with either the end wall 13 of the casting A or the transversely extending shelf and bearing plate thereof to limit the bodily shifting of the element B. The surfaces 26 perform this function until such time as either wing 23 begins to move under the overhanging edge of the plate 17, when the same function is performed by the inner curved surfaces 27. As an illustration, assuming the anti-friction element B in the extreme position indicated by dotted lines in Fig. 1, it is evident that the element B cannot be jarred to the left, since it is already in contact with the lefthand end wall 13 of the casting A. Obviously, the element B cannot be shifted bodily to the right unless it rolls, because of the fact that the lefthand wing 23 is in engagement with the shelf 15. In any intermediate position between the dotted line position and the full line position shown in Fig. 1, the wing 23 will be partly under the overhanging edge of the plate 17, and, consequently, the element B cannot be shifted laterally bodily to the right, and, obviously, the element B cannot be shifted bodily to the left, because of the proximity of the curved surface 26 and end wall.

By forming the combined counter weights and centering wings 23 in the manner disclosed, I am enabled to provide an unusually heavy counter balance, since the wings 23 may be made of comparatively thick metal, and, furthermore, extend the full length of the element B. This renders the return of the element B to center normal position un-

der the influence of gravity extremely sensitive and without the aid of a spring or other external means, such as have heretofore been common in anti-friction bearings, and which have proven a continual source of trouble. Furthermore, the element B is of such formation that it can be readily manufactured as a casting when the wings are formed integrally with the remainder of the anti-friction element. In the event the wings are made separately from the cylindrical section proper and thereafter the parts rigidly united, the roller section proper may well be made of high carbon rolled steel and the wings as ordinary castings. The bearing gives a true cylindrical roller action having all the advantages of the ordinary cylindrical roller bearing, and combines therewith, in a high degree, the gravity self-centering features of a rocker bearing and eliminates the disadvantages usually accompanying both of said types of bearings as heretofore employed in the art.

Although I have herein shown and described what I now consider the preferred manner of carrying out the invention, the same is merely illustrative and I contemplate all changes and modifications that come within the scope of the claims appended hereto.

I claim:

1. In an anti-friction bearing, the combination with a member having a bearing surface, of an anti-friction element adapted for a true rolling movement on said surface to either side of central normal position, and duplicate sets of coöperating means on said member and element, on diametrically opposed sides of the latter, to positively maintain a predetermined relation between said member and element in all positions of the latter, the portion of said means on said element being rigidly united therewith.

2. In an anti-friction bearing, the combination with a member having a bearing surface, of an anti-friction element adapted for a true rolling movement on said surface to either side of central normal position, and duplicate sets of coöperating means on said member and element, on diametrically opposed sides of the latter, to positively maintain a predetermined relation between said member and element in all positions of the latter, the portion of said means on said element being rigid therewith and normally depending below the rolling axis of said element and thereby adapted to act as a counter balance to return said element to central normal position after each actuation thereof upon removal of the actuating pressure.

3. In an anti-friction bearing, the combination with a retaining member and a bearing surface, of an anti-friction element having a true free rolling movement on said

bearing surface to either side of central normal position, said element having contact for its full length between its ends with said bearing surface, and coöperating means on said element and member limiting to a predetermined minimum the possible bodily offsetting of said element in a direction transversely of its axis to either side of normal central position, said means being duplicated on diametrically opposed sides of said element.

4. In an anti-friction bearing, the combination with a retaining member and a bearing surface, of an anti-friction element having a true free rolling movement on said bearing surface to either side of central normal position, said element having contact for its full length between its ends with said bearing surface, and coöperating means on said element and member limiting to a predetermined minimum the possible bodily offsetting of said element in a direction transversely of its axis to either side of normal central position, said means being duplicated on each side of said element and rigid with respect thereto, said means on the element, in conjunction with the latter, providing a center of weight below the rolling axis of the element, which center of weight is elevated when said element is rolled to either side of normal position and the same thereby adapted, under the influence of gravity, to return to central normal position after each actuation upon removal of the actuating pressure.

5. In an anti-friction bearing of the character described, the combination with a hollow retaining member and a bearing surface centrally disposed with respect thereto, of an anti-friction element having upper and lower concentric surfaces of equal radii, the lower surface of the element bearing upon the first-named surface, said element having diametrically disposed depending wings, each wing being curved, on its inner and outer face, the curved faces of the wings coöperating with adjacent portions of the retaining member to positively maintain a predetermined relation between the anti-friction element and said member in all positions of said element.

6. In a side bearing, the combination with a hollow retaining member having end walls and a transversely extending, centrally-disposed, elevated bearing surface, of an anti-friction element within said member, said element having a true roller section adapted to bear, throughout its entire length, on said bearing surface, said element having also counter weight sections on each side thereof, said counter-weight sections also normally straddling said elevated bearing surface.

7. As an article of manufacture, an anti-friction element for bearings, said element

comprising a central cylindrical section and integrally and longitudinally and downwardly extending wings on each side thereof.

8. In a side bearing for railway cars, the combination with a hollow substantially rectangular base casting having side and end walls and an elevated centrally disposed bearing surface, of an anti-friction element mounted within said casting, said element having a cylindrical section adapted to roll on said bearing surface, said element having also oppositely arranged depending wings integral with said cylindrical section, said

wings being curved on their inner and outer faces and co-operating respectively with the elevated portion of the base casting and the end walls thereof to positively maintain a predetermined relation between the base casting and the anti-friction element, said element having bearing contact with the bearing surface throughout its entire length.

In witness that I claim the foregoing I have hereunto subscribed my name this 15th day of March, 1919.

JOHN F. O'CONNOR.
